UNITED STATES PATENT OFFICE.

HIRAM GEE SEDGWICK, OF MILL VALLEY, CALIFORNIA, ASSIGNOR TO THE NATIONAL SAFETY APPLIANCE COMPANY, A CORPORATION OF CALIFORNIA.

AUTOMATIC TRAIN-STOP.

1,239,151.

Specification of Letters Patent.

Patented June 5, 1917.

Application filed June 4, 1909, Serial No. 500,103. Renewed December 9, 1916. Serial No. 136,062.

To all whom it may concern:

Be it known that I, HIRAM G. SEDGWICK, a citizen of the United States of America, and a resident of Mill Valley, county of Marin, State of California, have invented certain new and useful Improvements in Automatic Train-Stops, of which the following is a full and clear specification, reference being had to the accompanying drawings, in which—

Figure 1 is a diagram of a locomotive showing one form of my apparatus applied thereto;

Fig. 1* is a detail sectional view of a cut-off between the storage reservoir and the engineer's valve;

Fig. 2 is a vertical section, partly in side elevation, of the arm on the locomotive carrying the removable vent-piece;

Fig. 2* is a sectional view showing a modified form of vent-piece;

Fig. 3 is a vertical longitudinal section showing one of the roadbed shoes or hoods in operative relation to the removable vent-piece;

Fig. 4 is a vertical section of the train-pipe venting valve and the pneumatic motor adapted to open and close the same;

Fig. 5 is a detail side elevation of the vent-valve cylinder;

Fig. 6 is a detail section of the valve which controls the speed of opening the vent-valve.

Fig. 7 is a vertical sectional view of the valve located in the pipe-line for lowering and raising the laterally projecting arm on the locomotive.

Fig. 8 is a diagram of a portion of adjacent rail blocks showing one possible arrangement of the road bed system.

The object of this invention is to increase the reliability of the apparatus by doing away with all electric circuits on the locomotive and by providing means for operating the vent-valve which shall be positively controlled by pressure from the usual storage reservoir on the locomotive. The invention has other (minor) objects in view which will appear in the course of this specification.

Referring to the drawings by reference characters, *a* designates an extension of the train-pipe which enters the cylindrical vent-valve casing *b* through which works a plunger *c* provided with a longitudinal port

d in one side which, when the plunger descends, puts the train-pipe *a* into communication with the vent *e* and thus exhausts the train-pipe and applies the brakes, said vent *e* being preferably of tapering form 60 so that the exhaust will be graduated. While I prefer this manner of applying the brakes it is obvious that where electrical or other types of brakes are employed I may utilize the movement of the plunger *c* to 65 bring about the application of the brakes in any suitable manner.

The plunger *c* depends into a cylinder *f* and is attached to a piston *g* fitting said cylinder, and entering said cylinder above said piston is a pipe *h* leading from the usual storage reservoir *i*, and entering said cylinder below the piston is another pipe *j* leading from the train reservoir, the point of entrance of this latter pipe *j* being preferably 70 immediately below the piston when the same is in its upper or normal position, as shown in Fig. 4. The piston is held normally up by reason of the differential pressures on its opposite sides, this difference in pressure being equal to the cross-sectional area of the plunger *c*.

Entering the bottom of the cylinder *f* is a pipe *k* which extends downwardly and outwardly through a tubular arm *l* mounted on 85 the truck of the locomotive and extending horizontally outward beyond the wheels. This arm is provided at its outer end with a pair of separated upstanding fingers *m*, and the tube *k* is coupled at its extreme 90 outer end to a transverse port *n* in the upper end of one of said fingers. This port *n* is closed by a vent-piece *o* which is clamped over the end of the port and is held suspended between the fingers *m* by means of 95 a clamp-screw *p*. This removable vent-piece *o* may be made solid (as shown in Fig. 2) or hollow (as shown in Fig. 2*).

It will be observed that when the stopper or valve *o* is knocked out the cylinder *f* will 100 be vented through pipe *k*. This pipe *k* is larger in area than the inlet pipe *j* so that the air will exhaust from under the piston *g* faster than it can enter the same through pipe *j*, whereby the piston *g* will be forced 105 downwardly by the pressure admitted to the top of the cylinder through pipe *h* and thus apply the brakes as heretofore described. The inlet of pipe *j* is placed immediately under the piston *g* in order that the initial 110

movement of the piston will immediately cut off pressure from the reservoir and thus not only save air but permit quick operation of the vent valve. The speed of descent of piston γ may be regulated by the needle-valve q in pipe h , and in order that the motor cannot by any possibility be rendered inoperative by the closing of this valve the screw valve stem is provided with a shoulder r which is adapted to abut against an internal shoulder in the valve-casing and prevent the valve being entirely closed, as shown in Fig. 6.

The piston g and plunger e may be raised to their normal position after an operation, 15 by any suitable means but I prefer to employ reservoir pressure to restore the parts to operative position. One example of means for doing this is shown in Fig. 4. The port s leads into the bottom of cylinder f and communicates through a valve-casing t with an extension u of pipe h . In casing t is a valve v held normally closed by air pressure and a spring or other means, this valve normally cutting off pressure from the reservoir to the cylinder f . Normally closing port s is a slide cut-off w operated by a vertical rod x which rod is adapted to be alternately raised and lowered by means of 20 a tappet y attached to the upper end of piston e and adapted to work between stops z on said rod x . When the plunger e is operated cut-off w closes port s and thus cuts off the reservoir pressure from the lower extremity of cylinder f , whether or not valve v be closed or deranged in any way; but when piston g descends this cut-off w opens port s and holds it open while the piston is at the lower extremity of its stroke. After 25 the vent tube k has been closed by the insertion of another valve piece o the piston may then be raised to normal by simply opening valve v against reservoir pressure which, in view of the fact that said valve is 30 small, may be done manually.

In order that no derangement of the lifting devices could possibly interfere with the descent of the piston upon the venting of pipe z , I make the exhausting capacity of pipe z greater than the supplying capacity of both pipe y and port s combined, so that even were port s and pipe y at all times open to reservoir pressure the venting of pipe z would exhaust more air than could enter the cylinder and thus insure the descent of the piston upon the venting of pipe z .

In order that air shall not be supplied to the train-pipe through the engineer's valve from the reservoir while it is being exhausted through vent e and thus not only waste air but interfere with the quick application of the brakes, I provide a cut-off b in the pipe a' at a point between the reservoir and the engineer's valve c and this cut-off is 40 automatically operated by the descent of

the plunger e . A simple form of cut-off consists of a plunger-like extension d' of the piston e working through a vertical cylinder e' inserted in the pipe a' , said plunger d' being provided with an annular port f' which when the plunger is up gives a free passage of the air through pipe a' but which when the plunger descends closes pipe a' . At one side said port f' is provided with an upward extension g' which when the plunger descends puts the reservoir in communication with a whistle h' or other audible alarm and thus causes a continuous alarm to be sounded while the brakes are on.

Any suitable means may be mounted on 45 the roadbed at danger points to knock out the vent pieces o . I prefer the means shown in my co-pending application Serial No. 498,433, consisting of casings mounted at intervals along the roadbed and each 50 provided with a magnetically controlled 55 gravitating hook i adapted when set to danger to depend through a slot in the bottom of the casing. This hook i is attached to a pivoted armature j insulatedly supported on the bottom of the casing; in the present instance. This armature and its hook is included in the normally-closed circuit with the magnet k' , one of the wires being attached to the hook near its extremity and 60 the other being connected to the armature at any suitable point. The object of this wiring arrangement is to cause the signal devices (if any be employed) together with any other disrupting or dislodging hooks i 65 that may be in the same circuit to be set to danger in case the point of the hook should become broken off and thus rendered ineffective.

It will be observed that the outwardly 70 projecting arm l may be duplicated on the other side of the locomotive so as to protect the train in backing, but this duplicate arm will operate in connection with reversed disrupting hooks i' . Where this duplicated 75 arm arrangement is employed it is advisable that a hinged cam plate k' be employed between the fingers m to lift any hook i' that may be set to danger.

At the left-hand side of the locomotive this guard or cam plate k' 80 is pivoted between the fingers m at a point back of the valve piece o and extends upwardly and forwardly to a point above the same, so that when the arm backs under a set hook this guard plate k' will lift the hook 85 and prevent it dislodging the valve piece o . A spring l' normally swings this guard plate k' forward against a stop m' but permits it to yield backwardly to permit a set hook to pass between the fingers m . This guard plate, however, will not be essential if a sufficiently rigid valve piece o be employed to itself lift a set hook in going in the reverse direction.

It is necessary at times that a locomotive 90

be permitted to pass by a set disrupting hook without dislodging the valve piece *o*. For this purpose I so mount the arm *l* that it may be lowered sufficiently to bring the 5 part *o* out of alignment with the set hooks. The inner end of the arm *l* is provided with a cross-head *n*' which is supported upon the upper end of a piston rod *o*' attached to a piston *p*' working in a vertical cylinder 10 *q*' mounted on the truck. Reservoir pressure is supplied under this piston to normally hold it up by means of a pipe *r*' which is connected to pipe *a*' through a valve *s*'. This valve may be of any suitable construction 15 such, for instance, as that shown in my co-pending application Serial No. 498,453. Air normally passes through this valve but when its plug is rotated toward the cab through the medium of its depending arm 20 *t*' the supply from pipe *a*' will be cut off and pipe *r*' will be exhausted to the air and thus lower the arm *l*. Valve arm *t*' may be operated in any suitable way as, for instance, by an angle-lever *u*', connected by a 25 wire or rod *v*' to an arm on the usual cut-off *w*'. By means of the cut-off *w*' the engineer can cut out his control-valve entirely when running tandem and, at the same time, he will render the automatic devices on his 30 locomotive inoperative. To keep tab on the

engineer a register *x*' may be attached to the wire *v*' so as to make a record of every time the automatic devices are thrown to inoperative position.

I make no claim in this application to anything covered by claims in my co-pending applications serially numbered respectively, 480,900 and 498,453. 35

Having thus fully described my invention, what I claim as new and desire to secure by Letters Patent, is:— 40

In an automatic train stop, a brake controlling means on the locomotive, a pneumatic motor for operating the same and means for connecting the motor to a storage reservoir, means for governing the supply to the motor to cause the same to operate and apply the brakes, means for restoring the motor to operative position, these means embodying a cut off automatically opened and closed by the action of the motor. 45

In testimony whereof I hereunto affix my signature in the presence of two witnesses this 4th day of June, 1909.

HIRAM GEE SEDGWICK.
